UNITED STATES PATENT OFFICE.

ARTHUR H. FETTERS, OF OMAHA, NEBRASKA.

CASING FOR LOCOMOTIVE STEAM PIPES.

Application filed June 15, 1923. Serial No. 645,645.

To all whom it may concern:

Be it known that I, ARTHUR H. FETTERS, a citizen of the United States, residing at Omaha, in the county of Douglas and State 5 of Nebraska, have invented certain new and useful Improvements in Casings for Locomotive Steam Pipes, of which the following is a specification.

This invention pertains to casings for the 10 outside steam pipes of locomotives or for those portions of the steam pipes which pass through the shell of the smoke-box and thence to the valve-chests of the locomotive cylinders.

15 The purposes of the invention are, to produce a relatively inexpensive casing which shall hermetically seal the openings through which the steam pipes pass, so that there may be no ingress whatever of air to the 20 smoke-box, and which though permitting or compensating for expansion and contraction due to heat, and play incident to vibration of the locomotive, shall nevertheless maintain a perfect sealing of the openings for an 25 indefinite period. The construction is such that packing glands are avoided, and heavy and expensive fittings are dispensed with.

The invention is illustrated in the accompanying drawing, in which:

30 Figure 1 is a fragmentary section of the smoke box shell, the external portion of one of the steam pipes, the sealing casing, and the external casing extending from the smoke-box to the valve-chest; and

35 Figure 2 is a plan or face view of a plate applied to the interior of the smoke-box shell and through which the steam pipe passes.

In these drawings, 1 indicates the shell of 40 the smoke-box provided with an opening 2 considerably larger than and thus facilitating the introduction of the outside steam pipe 3. 4 indicates the valve-chest provided with a flanged neck 5 with which the steam 45 pipe 3 makes connection, preferably by a spherical joint 6, as is usual in locomotive construction. The opening 2, which is circular, is partly covered and reduced by a metallic plate 7 of the form shown in Fig. 2, 50 and having an opening of like form. The elliptical or elongated form of the opening is rendered necessary by reason of the curvature and inclination of plate 7 relative to the steam pipe 3, it being desirable that the 55 inner edge or wall of the opening in plate 7 have a slight clearance with reference to

the pipe 3. The plate 7 is secured to the inner face of the smoke-box shell 1, preferably by spot welding, though I do not restrict myself to this particular mode of attachment. It is so secured after the steam pipe 3 has been properly positioned.

In practice it is found desirable to make the plate 7 in two like sections so that it may be readily placed about the steam pipe after 60 the latter has been properly positioned, but if there be no enlargements at the ends of the pipe section it may be made in a single piece and passed over the end of the pipe preparatory to setting the latter. As the 70 plate is of relatively thin material, it is possible to cut it at one end only and bend the two sides apart facewise, pass it about the pipe and into position, and bring the free ends again into common plane, but the two-part plate is found simple and convenient of application and is hence preferred.

Encompassing that portion of the steam pipe 3 immediately outside the smoke-box shell 1, and for some distance below the 80 same, is a cylindrical casing 8, the upper end of which is provided with an outwardly turned flange 9, the face of which is curved to conform to the outside curvature of the smoke-box shell where, as in the present instance, the steam pipe is arranged vertically. The angularity of said face will be varied to correspond to any change of the position of the steam pipe from the vertical. The lower end of the casing 8 is reduced in 85 diameter to form a neck 10, which makes a close contact or fit with the circumference of steam pipe 3 or with a swell or enlargement 11 made thereon, that portion of the casing 8 between its main body or portion of larger diameter and the neck or sleeve 10 being formed by a reversed or ogee curve 12, as shown in the drawing. The neck or sleeve 10 is preferably electrically welded to the steam pipe, and the flange 9 100 is similarly welded to the outer face of the smoke-box shell 1, thus producing air and gas tight joints between the steam pipe and the smoke-box shell, and hermetically sealing the latter against ingress of air 105 through the openings 2.

13 indicates a light outer casing of sheet metal, which is preferably made in two halves to facilitate application and removal. These sections are flanged at their 110 lower ends to conform to the circumference of the valve-chest when the latter is of

cylindrical form, and are cut on a curve at their upper ends to conform to the curvature of the smoke-box shell and of the flange 9 of the inner casing 8. The sections of the 5 casing 13 may be connected in any convenient way, either by bands or hoops passing about them, or by bolts passing through ears 14 formed thereon.

The bolts connecting the flanges of the 10 steam pipe 3 and valve-chest neck 5 are omitted in the drawing for greater clearness in the showing of the parts, but will of course be used in practice.

The space bounded by the inner walls of 15 casing 8 and the outer walls of steam pipe 3 and plate 7 may be advantageously packed with asbestos or other heat-resistant material, if desired, in the form of asbestos rope, this serving to lessen the radiation of 20 heat from and the cooling of the steam pipe. Packing may if desired be applied within the outer casing 13 for a like purpose.

While in practice it is deemed advisable to employ spot welding for the attachment of 25 plate 7 to the smoke-box shell, and electric welding for securing the casing 8 to the smoke-box shell and steam pipe, it is obvious that other methods of securing said parts and forming a gas and air tight union 30 between them, may be employed. I do not, therefore, intend to restrict myself to welding, but contemplate any other usual or known and efficient method of making such connection.

25 The reversed or ogee curve connecting the larger and smaller diameters of the casing 8 ensures a flexibility and permits a limited play of the pipe 3 without producing any initial lines of fracture such as would be 40 offered by sharp bends or angles.

The structure here set forth has been practically tested for a considerable period of time in regular railway service, and such tests have demonstrated its efficiency, 45 permanency, and absolute freedom from air leaks. It thus overcomes a serious difficulty long and generally experienced in locomotive construction, seriously affecting the draft of the engine, and involving material 50 waste of fuel.

The use of the light outer casing 13 is optional, though usual and preferred. The prominent feature of the invention is the inner casing having the reversed curve affording flexibility and permitting, without injury, loosening of parts, or breaking of the seal, such play and vibration as is incident to the motion of the locomotive and the relative movement of its parts.

60 What is claimed is:—

1. In a locomotive, the combination of a smoke-box; a valve chest; a steam pipe passing through the smoke-box shell and connecting with the valve chest; and a casing 65 encompassing said steam pipe, joined at

one end to the smoke-box shell and at its other end to the steam pipe, and serving to seal hermetically the opening in the smoke-box shell through which the steam pipe passes.

70 2. In a locomotive, the combination of a smoke-box; a valve chest; a steam pipe passing through the smoke-box shell and connecting with the valve chest; and a casing encompassing said steam pipe, joined at one end to the smoke-box shell and at its other end to the steam pipe, and having intermediate said points of connection a reversed curve connecting its portions of larger and smaller diameter; whereby flexibility is afforded said casing and play of the steam pipe is permitted without danger of rupturing the casing or its connections with the smoke-box shell and the steam pipe.

75 3. In combination with the shell of a locomotive smoke-box provided with an enlarged opening for the introduction and passage of a steam pipe; a valve chest; a steam pipe passing through said opening in the smoke-box shell and communicating with the valve chest; a plate secured to the inner wall of the smoke-box shell, projecting inward over the opening therein, and through which the steam pipe passes; a casing encompassing the steam pipe and having a flanged upper end firmly secured to the exterior face of the smoke-box shell, and its lower end formed into a close-fitting sleeve and secured to the outer surface of the steam pipe; and an outer casing encompassing the first casing and the steam-pipe, and extending from the smoke-box shell to the valve chest.

80 4. In combination with the smoke-box shell of a locomotive, a valve chest; an external steam pipe; a casing encompassing said steam pipe and welded at its upper and lower ends to said shell and steam pipe; and an outer casing encompassing the first-named casing and the steam pipe, and extending from the smoke-box shell to the valve chest.

85 5. In combination with the smoke-box shell of a locomotive, and with a valve chest, a steam pipe passing through an opening in said shell and communicating with the valve chest; a metallic casing encompassing the steam pipe, having its upper end hermetically secured to the smoke-box shell and its lower end contracted and hermetically joined to the steam pipe; and a heat-resistive packing interposed between the steam pipe and the casing.

90 6. In combination with the smoke-box of a locomotive having a relatively large opening through its circular wall to permit ready introduction of the outer section of a steam pipe; a valve chest; a steam pipe of smaller diameter than and passing through said opening to and connecting with the valve

chest; a plate within the smoke-box, conforming to the curvature of the smoke-box wall, and through which said pipe passes; and a casing encompassing the steam pipe, hermetically secured at its upper end to the smoke-box wall and at its lower end to the steam pipe, and having between said points of attachment a reversed curve affording flexibility and permitting relative play of the parts.

5 In testimony whereof I have signed my name to this specification.

10

ARTHUR H. FETTERS.
